AIR HEATER AND CIRCULATOR

Frank R. Higley, Cleveland Heights, and Eric H. Ryden, Elyria, Ohio, assignors to Bryant Heater Company, a corporation of Ohio

Substituted for abandoned application Serial No. 406,500, August 12, 1941. This application February 8, 1946, Serial No. 646,414

2 Claims. (Cl. 126—110)

1

This invention relates to improvements in air heaters and circulators, in other words apparatus for heating and circulating air. With respect to certain of its features the present invention resembles to some extent that of our co-pending application Serial No. 393,302, filed May 13, 1941, and now Patent No. 2,361,545, dated October 31, 1944. This application replaces application Serial No. 406,500, filed August 12, 1941, by the applicants herein and since held abandoned.

One of the objects of the present invention is the provision of a forced air heater embodying a blower having a horizontal rotor and a scroll, a portion of which consists of a hollow casting constituting a conductor for hot gases, this casting serving for combustion chamber and that portion of the curved scroll wall along which flows the relatively high velocity air, that is to say the portion which is nearest the rotor.

Another object of the invention is to permit the use of a relatively short casting for the purposes above indicated, thereby reducing the difficulties in the pouring of the casting.

Another object is to provide three successive heat exchange surfaces over which the air to be treated must pass, thereby insuring high efficiency.

Other objects and features of novelty will appear as we proceed with the description of that embodiment of the invention which, for the purposes of the present application, we have illustrated in the accompanying drawing in which

Fig. 1 is a side elevational view somewhat diagrammatic in character and partly in vertical section, of a furnace embodying the invention.

Fig. 2 is a horizontal sectional view of the same, taken substantially on the line 2—2 of Fig. 1.

Fig. 3 is a detail sectional view on a larger scale taken substantially on the line 3—3 of Fig. 1, and

Figs. 4 and 5 are fragmental plan views, also on a larger scale, of the two ends of the flue connection shown in Fig. 3.

In the drawing, a rectangular sheet metal casting constituting the outer wall of the furnace is shown at 10. It is provided at the top with an opening 11 for the admission of air to be heated, and an air filter shown conventionally at 12 is provided inside the casing in order to remove any dust carried by the entering air.

The base 13 of the casing which, of course, may be suitably re-enforced, supports a hollow metal casting 14 which is elongated in a generally upright direction. As indicated in Fig. 2 this casting may be of substantially square section at

2

the base. Its transverse dimension remains substantially the same throughout its height, but its dimensions from front to rear decrease materially above the base portion, as will be evident from an inspection of Fig. 1.

A burner of any suitable character is mounted in the base portion of the casting, a gas burner 15 being illustrated herein with the controls 16 therefor in a separate chamber 17 formed by one wall of the casting 14 and sheet metal partition members in the lower portion of the space enclosed by the casing.

A part 18 of the rear or inner wall of the casting is curved spirally. Its front wall slopes toward the rear, as shown in Fig. 1, with the result that the passage through the hollow casting is constricted considerably near the top. An opening in this front wall covered by a removable cap 19 serves to admit a brush or other tool when the interior of the casting requires cleaning. If desired, the front and rear walls may be ribbed to provide increased surface in the manner indicated in our co-pending application above referred to.

The wall 18 constitutes part of the spiral wall of the scroll of a centrifugal blower, the rotor shaft of which is illustrated at 20. The periphery of the wheel or rotor is indicated by the dotted line 21. The two side walls of the scroll, one of which is shown at 22, overlap slightly the casting 14 and are suitably secured thereto. The scroll also has a sheet metal curved wall portion 23 which constitutes a continuation of the wall 18 of the casting. Bearings for shaft 20 are suitably supported preferably from the side walls 22 of the scroll, and the side walls have openings at opposite ends of the rotor for admission of air thereto. A pulley 24 on the shaft is driven by a belt 25 which runs over the pulley of an electric motor 26 that may be supported above the base 13 of the casing on a bracket 27. 28 is an air delivery extension of the blower scroll protruding through the top of the casing 10 to which the warm air ducts of a heating system may be connected.

A partition 29 extends entirely across the casting in front of the extension 28 down to the side plates 22 of the scroll, and from that point partitions 30 bridge the spaces between the scroll and the two side walls of the casing down to a level below that of the rotor shaft. Consequently air entering the furnace must flow downwardly over the outer or front wall of the casting 14 past the bottom edges of partitions 30 before it can enter the blower.

At the rear of the casing a flue pipe 31 joins a flue connection 32, the latter extending horizontally across the delivery extension 28 of the blower and being attached at its forward end to the upper extremity of the casting 14. This flue connection may be formed of sheet metal if desired, but we show it as a casting which, as shown in Fig. 3, may be ribbed to increase its heat transfer surface. As will be noted from Fig. 3 this flue connection member is streamlined in cross section so as to reduce air friction to a minimum, and the fins or ribs are arranged in the direction of air flow for a similar purpose. Hot products of combustion from the burner 15 flow upwardly through the hollow casting and thence through the flue connection 32 out through the flue pipe 31.

A water pan or trough 33, in which water is preferably maintained at a constant level automatically by suitable known means, not shown, serves to humidify the air before it enters the blower.

In blowers of the type illustrated the velocity of the air flowing through the spiral path is greatest at the most constricted part of that path, that is where the curved wall of the scroll is closest to the rotor. If a portion only of the encircling wall of this path is to be heated it is important that such portion be that where the air travel is most rapid, because then the rate of heat exchange will be high. For that reason we have placed the curved surface 18 of our casting adjacent the cut off end 34 of the scroll spiral; that is, we have arranged one end of it near the point where the curved scroll wall is nearest the rotor and have continued it from that point through a substantial angle, in the illustrated case an angle between 90° and 180°.

The lower part of the curved wall 18 of the casting is purposely exposed to radiant heat from the burner in a degree which would be destructive were the furnace a gravity furnace. The rapid flow of air over this surface due to its being part of the blower scroll, however, maintains this wall at a safe temperature. Higher up on the wall 18 the heating effect is, of course, due to convection only, which is likewise the case with respect to the flue connection 32. The rear wall of the casting 14 is also heated by convection. It will be seen, therefore, that the air to be treated strikes the front wall of the casting first, where it is preliminarily heated. Next it passes into the blower and is moved thereby rapidly over the wall 18, first in the convection-heated portion and then in the portion heated by radiant heat, after which it travels over the flue connection 32 heated by convection.

The construction is exceedingly compact, and covers a wide range of heat requirements at an efficiency which remains almost constant over that range.

It would be possible to apply heat to the scroll wall through a somewhat greater angle than that

illustrated, but that would mean a larger hollow casting, and castings of this kind are difficult and costly to produce. In the present instance by utilizing the flue connection 32 we have not merely compensated for heating a limited length of the scroll but have, in fact, increased the total heating area and the total heating effect over what could have been attained by the use of a longer casting 14. Furthermore, whether the flue connection 32 be a casting or a sheet metal member, the cost of the two parts 14 and 32 will be appreciably less than the cost of a single casting taking in another considerable portion of the scroll wall.

We claim:

1. In an air heater and circulator, a centrifugal blower comprising a rotor and a scroll, the rotor having a horizontal axis, a delivery extension for the blower, a combustion chamber and a conductor for all gases therefrom constituting that side of the scroll which is radially innermost, said conductor extending into the angle between the scroll and the extension, means for directing entering air against said conductor adjacent said angle, a flue connection positioned across the extension and connected with the outlet end of said gas conductor, the passage for hot gases varying in shape from the gas conductor where the transverse dimension is the greater, to the said flue connection, where the dimension in the direction of air flow is the greater.

2. In an air heater and circulator, a centrifugal blower comprising a rotor and a scroll, the rotor having a horizontal axis, a delivery extension for the blower, a combustion chamber and a hot gas conductor constituting that side of the scroll which is radially innermost, said conductor extending around the innermost part of the scroll into the angle between the scroll and the said extension, a flue connection positioned across the extension and connected with the upper end of said gas conductor, and a clean-out door in the outer wall of said gas conductor adjacent said angle, whereby a cleaning brush may be inserted through the said door downwardly into the gas conductor or through the said conductor into said flue connection.
